UNITED STATES PATENT OFFICE.

HENRY W. KIRCHNER, OF ST. LOUIS, MISSOURI.

SYSTEM OF TRANSPORTATION.

Application filed July 25, 1921. Serial No. 487,309.

To all whom it may concern:

Be it known that I, HENRY W. KIRCHNER, a citizen of the United States, residing at city of St. Louis, State of Missouri, have invented a certain new and useful Improvement in Systems of Transportation, of which the following is a full, clear, and exact description, such as will enable others skilled in the art to which it appertains to make and use the same, reference being had to the accompanying drawings, forming part of this specification.

My invention relates to transportation systems in which shipping containers are adapted to be assembled with various types of carriers to facilitate the transfer of merchandise from one carrier to another or from carrier to warehouse, and vice versa.

My invention consists of various improvements upon containers and cooperating carrier mechanism of the general type disclosed in my copending application Serial No. 468,397 filed May 10, 1921.

One object of my invention is to provide means for more easily positioning the container on the carrier and to render such means effectively operative when containers of different sizes are used on the same carrier.

An additional object of my invention is to provide an improved container securing mechanism on the carrier. When containers of this type are used in railway service, it is desirable that they conform to the standard outline of railway box cars, and a further object of my invention is to provide a container which is adapted to form, when assembled with other container units, a box car superstructure which will in all essentials be the substantial equivalent of an ordinary box car.

Further objects of my invention are to more economically construct the individual containers and to render them more rigid and better adapted for transfer from carrier to carrier or warehouse.

In the accompanying drawings which illustrate a selected embodiment of my invention—

Figure 1 is a top view of a transportation unit comprising a flat car upon which several of my containers are mounted. While one half of the car is shown with these containers to more clearly illustrate the detail construction, it is to be understood that the carrier may be used as shown, or with a

maximum number of containers mounted thereon, or with any smaller number arranged in any convenient location on the carrier.

Figure 2 is a side elevation of the unit shown in Figure 1.

Figure 3 is an end elevation of one of the containers.

Figure 3^a is a plan view partly in section of one of the containers.

Figure 4 is a side elevation of the container shown in Figure 3.

Figure 5 is a vertical transverse section through the floor of the carrier near its transverse center and showing the container holding mechanism including a keeper element mounted on the bottom of the container.

Figure 6 is a top view of the carrier floor in the neighborhood of one of the container holding mechanisms and showing the latter in retracted position.

Figure 7 is a similar view, but showing the mechanism in its projecting position in which it is adapted to secure the container.

Figure 8 is an elevation of the side of the car showing one of the securing mechanism operating handles and locking devices therefor.

Figures 9 and 10 are, respectively, a top view of and a vertical section through a container positioning device.

Figure 11 is a fragmentary end elevation of the container shown in Figure 3, but on a larger scale to better illustrate the details of its construction.

Figure 12 is a side elevational view of a modified form of handle lock.

Figure 13 is a vertical sectional view illustrating said handle lock.

Figure 14 is a perspective detail of the container keeper element.

The carrier shown in the accompanying drawings consists of a railroad flat car, but it is to be understood that for the purposes of my invention, it might be a steam-boat, a barge, or a motor truck. The floor of this car is flat to enable it to be used in the usual manner for ordinary flat car loads. All of the container positioning and holding mechanism is adapted to be retracted to or below the floor level so as not to interfere with such loading of the flat car.

To provide the most elastic form of my system, the containers are made in various sizes ranging from that shown in Figures 3

and 4 to a container equal to substantially four of the containers there detailed.

In Figures 1 and 2, I show two of the smallest containers 1 and 2, a "double" container 3, and a "quadruple" container 4, the latter being located at the end of the car.

It is to be understood that these containers may be placed in other positions on the car and on the lefthand side of Figure 1, I 10 have indicated in dot-and-dash lines a different arrangement of the same containers in which the smaller units 1^a and 2^a are located at the end of the car, and a "double" unit 3^a is located next to 1^a and 2^a, 15 and the "quadruple" unit 4^a is located nearest the center.

In order to properly assemble the carrier and the containers, it is of course necessary for the latter to be accurately placed on the 20 carrier and to secure accurate positioning of the containers, I provide each of them with spherical protuberances 5 on its bottom and I provide the carrier floor with crater-like recesses 6, 7, 8, 9, 10, 11, adapted to receive 25 protuberances 5 and automatically center the latter.

Where the container forms a portion of the end of a car, it is of course necessary that the container be turned in the right direction. Each container preferably has a sloping roof and carries a section of running-board and it is necessary that this be rightly positioned. The single containers preferably have their side doors positioned along 30 the longitudinal center line of the car to prevent opening of the doors except when the container is removed from the car. To avoid the turn of the container when assembled with the car so that the above essentials are 35 not obtained, I arrange protuberances 5 and recesses 6 in such a manner that they will only cooperate when the container is turned in the right direction.

The asymmetrical arrangement shown in 40 Figure 1, provides three cooperating protuberances and craters for each of the smallest containers. These are arranged at the apices of isosceles triangles.

Positioned centrally of each triangle 50 formed by the craters 6, 7, 8, is a container holding mechanism each comprising levers 12 and 13 mounted on parallel shafts 14 and 15, respectively, and provided with arcuate shaped engaging surfaces 16 and 17, respectively. Shafts 14 and 15 are disposed transversely of the car and shaft 14 extends 55 through the side sill thereof and is provided with an operating handle 18. Shaft 14 is squared to secure positive rotation of lever 60 12 therewith. Shaft 15 is loosely mounted on the car walls and is only long enough to provide a suitable journal for levers 13. Levers 12 and 13 are provided with intermeshed spur teeth 19 so that positive rotation 65 of lever 12 provides a rotation of levers

13 in the opposite direction. These levers may be projected from the position shown in dot-and-dash lines in Figure 5, (where the ends of the levers form a continuation of the top surface of the car floor), to a position indicated by the solid lines in which the levers have moved over arcuate keeper elements 20 mounted on the bottom of the container. These elements 20 are here indicated as portions of a casting having a flat lower face 70 lying in the same plane as the bottom of the container sills 32 and arcuately upwardly facing surfaces between which and the bottom of the container proper there is sufficient space for the insertion of the heads of levers 75 12 and 13. These upwardly facing surfaces are three in number for each container, arranged end to end, the center surface being offset transversely of the two side surfaces 80 (see Figure 14). These arcuate surfaces correspond to the arcuate downwardly facing 85 engaging surfaces of the ends of levers 12 and 13. The centers from which these arcuate engaging faces are described are the centers of the respective shafts and when the 90 levers are in locked position any tendency of the container to tilt will be effectively resisted not only by the direct grip of the lever, but by the leverage which the lever has due to the length of the flat bottom surface of the 95 keeper element 20 in contact with the top of the carrier floor.

A handle locking pawl 21 is pivoted on the side of the car in a position to engage a side 100 of handle 18 thereby preventing rotation of the handle in the direction of the arrow A, which is the direction the handle must be turned to unlock the container holding mechanism. The engagement of pawl 21 with handle 18 is of a wedge nature and securely 105 holds the latter. An additional precaution against unauthorized unlocking of the holding mechanism is provided in the form of a sealing wire 22 and a conveniently arranged 110 staple 23.

My improved container shown in the accompanying drawings is rendered rigid by the application of structural members, here 115 shown as rolled channels 24 of inverted U-shape, each of which extends along two vertical edges and across the top of one side of the container. Flat bars 25 extend diagonally from the bottom of each leg of channels 24 upwardly and inwardly towards the center and top of the container where they unite 120 and at this point have a lifting ear 126 secured to them.

This construction enables the container to 125 be lifted by ears 126 without any undue racking or wearing of the container walls. The lower ends of each bar 25 are flanged outwardly and riveted to the adjacent ends of channels 24. Bars 25 being tension members require no stiffening flanges and thereby permit the addition of a ladder comprising 130

ing stiles 26 and 27 and rungs 28 without undue projection of the ladder from the end of the container. The stile 27 preferably consists of an angle iron riveted to the adjacent flange of channel 24 which at once stiffens the stile and protects it from side swiping or other accident. Each of the containers is provided with a section of running-board extending longitudinally of its highest roof portion and in addition thereto a running-board section extending at right angles to the above mentioned section along one edge of the container roof for the use of a trainman climbing to the roof of the 15 container. With "double" and "quadruple" containers, the doors will be on the outside and in the case of a "quadruple" container, will be much wider than the doors of the single or double containers. This will enable the "quadruple" containers to be used 20 for bulky merchandise, such as furniture and machinery.

In Figures 12 and 13, I have shown a modified form of handle lock in which the 25 handle 18^a mounted on the squared end of the operating shaft is provided with a recess 18^b. There is a rod 30 mounted in suitable brackets on the side sill of the car, said rod carrying hooked rock arms 31 which are designed to lie along side of the handle 18^a when the container engaging hooks are retracted and to enter the recess 18^b with its hooked end under the operating handle when the container engaging devices are projected. 30 Suitable means for locking and sealing this hook carrying rod may be provided and said rod may extend throughout the entire length of the car or only a portion thereof, as desired. The purpose of its rocking 35 hooks are to engage the operating handles and lock them when the container engaging devices are retracted or projected.

It will be observed that the container units, or a multiple thereof, are interchangeable between the carriers of the same or different kinds and which identical or different carriers are provided with the same crater-like recesses and fastening devices.

The staggered relation of the container keeper elements 20 is necessary because the 50 engaging fastening devices are mounted on different centers. In the arcuate movement of these fastening devices, they pass each other in arcs of different centers, which arcs 55 of course intersect each other. When the fastening hooks are engaged with their keepers, which keepers are provided with a flat bearing surface, in engagement with the platform of the car, it will be obvious that 60 any movement of the keeper element in a horizontal plane or a plane parallel to the surface of the car platform, will cause the hooks to more tightly bind and grasp the keeper elements. In other words, by the 65 construction shown neither hook will be

loosened by tendencies to shift the containers or by any other force except those applied about their shafts.

The arrangement of the crater-like centering plates 6—7—8 and 9—10—11, is such 70 that, a large container can be arranged at the end of the car, as shown at the right in Figure 1, or a double or two single (unit) containers may be arranged at the end of the car. If it is desired to eventually place two 75 single or a double container at the end of the car, and to first arrange a large container next adjacent to the space to be occupied by the smaller containers, the location of the crater-like recesses (see lefthand side of 80 Figure 1) will prevent the large container from becoming properly seated until it is in its exact intended position. In other words, it can not overlap the space intended for the smaller containers and be properly seated; and until it is properly seated, the fastening devices can not be properly engaged therewith. This provides the necessary space required to lock the carrier with 85 containers large or small, or both, to its maximum capacity. As shown in Figure 1, there can be four large containers arranged on the carrier, eight double containers, or sixteen small (unit) containers, or a mixture of 90 some or all of these. The distance between 95 the crater-like-recesses, say, 6—7 of one group being different from the distance between, say, recess 6 and the nearest crater-like recess of the next adjacent group insures the above arrangement. 100

I claim:

1. The combination of a transportation carrier member and a removable freight container member adapted to be placed in different locations on said carrier, there being 105 relatively small protuberances on one of said members and shallow crater-like recesses on the other of said members for cooperative engagement for determining the positioning of said container on said carrier irrespective of the location of the container.

2. The combination of a transportation carrier and a removable freight container, 110 asymmetrically arranged crater and protuberances on said carrier and container, respectively, for insuring predetermined positioning of the container on the carrier relative to the edges of the carrier and to other containers which may be mounted thereon.

3. The combination of a carrier member and a removable container member, there being asymmetrically arranged protuberances on one of said members, and crater-like recesses on the other of said members for cooperative engagement and locking means 115 which are inoperative unless said protuberances and recesses are in engagement.

4. The combination of a carrier member and a removable container member, there being protuberances on one of said members, 120

- crater-like recesses on the other of said members for cooperative engagement, and means for locking the parts together during such interengagement.
5. The combination of a carrier car and a plurality of removable containers each provided with typical box car equipment required to be in predetermined relation to a car body, and means for insuring the proper 70 positioning of the containers on the carrier so that when the carrier and containers are assembled said equipment is located in proper position relative to said carrier.
6. In combination with a carrier, a removable container, securing means on said carrier and container adapted to cooperate when said container is in predetermined relation to said carrier, and means for automatically positioning said container on said 75 carrier when same are assembled so that said securing means may function.
7. In combination, a carrier, a plurality of removable containers, container positioning elements arranged on said carrier so 80 that each of said containers can only be mounted on said carriers in a predetermined relation which will permit the mounting of the maximum number of containers on said carrier.
8. In combination, a carrier, a plurality of removable containers of different sizes, container positioning elements on said carrier so arranged that larger containers can only be mounted on the carrier in positions 85 which will permit smaller containers to be assembled therewith to maintain the maximum capacity of the carrier.
9. In combination, a carrier, a plurality of removable containers of different sizes 90 formed in multiples of the smallest unit, and container positioning elements the length of said carrier and the location of said elements being such that said containers may only be positioned to permit complete loading of said carrier.
10. In combination, a carrier, a removable container, a group of protuberances on said container, and a plurality of groups of cooperating recesses on said carrier so arranged 95 that the protuberances on said container can only cooperate with the elements of a single group of recesses on said carrier.
11. In combination, a carrier, a movable container, three positioning elements triangularly arranged on the bottom of said container, groups of three cooperating triangularly arranged positioning elements on said carrier, the distance between any two carrier elements of separate groups differing 105 from the distance between any two carrier elements of the same group.
12. The combination of a carrier member, a removable container member, one of said members having convex keeper elements and the other of said members having 110 arcuate fastening elements, and means for imparting an arcuate movement to said fastening elements for engagement with said keeper elements.
13. The combination with a carrier member, a removable container member, one of said members having keeper elements and the other of said members having oppositely movable fastening elements for conjoint engagement with said keeper elements. 115
14. The combination with a carrier member, a removable container member, one of said members having keeper elements and the other of said members having oppositely movable fastening elements staggered with 120 relation to each other for conjoint engagement with said keeper elements from opposite sides.
15. The combination of a carrier member, a removable container member, keeper elements on one of said members, and movable fastening elements on the other of said members adapted, respectively, to engage said keeper elements from opposite sides and each engaging its respective keeper element substantially throughout the entire 125 width of the latter.
16. The combination of a carrier member, a removable container member, keeper elements on one of said members, and movable fastening elements on the other of said members adapted, respectively, to engage said keeper elements from opposite sides and each engaging its respective keeper element at opposite sides of the latter. 130
17. In combination, a carrier, a removable container mounted thereon, a keeper element on said container having an upwardly facing arcuate engaging surface, a fastening element on said carrier having a corresponding downwardly facing arcuate engaging surface, and means for moving said fastening element in the arc of said engaging surface into and out of engaging position.
18. In combination, a carrier, a removable container mounted thereon, a keeper element on said container having an upwardly facing arcuate engaging surface, a fastening element on said carrier having a corresponding downwardly facing arcuate engaging surface, said fastening element being pivoted to said carrier on the given center of the arc of said arcuate engaging surface. 135
19. In combination, a carrier, elements having arcuate engaging surfaces and provided with parallel shafts on said carrier, a container, keepers on said container having arcuate engaging surfaces offset in the direction of their chords, and means for simultaneously rotating said elements to engage said keepers. 140
20. In a container of the class described, a continuous structural member extending around opposite vertical edges and across 145

- the adjacent top edge of the container, upwardly converging elements extending from the lower portions of said member, and lifting ears secured to said elements 40
- 5 near their convergence.
21. In a container of the class described, a structural frame member located along one vertical edge of the container, and a ladder positioned adjacent to said member with 45
- 10 a stile protected thereby.
22. In a container of the class described, structural frame members arranged along the vertical edges of one end of said container, outstanding flanges on said members, inclined flat bars converging towards each 50
- 15 other at the top of the container, a ladder stile secured to one of said outstanding flanges, a ladder stile spaced therefrom, and rungs between said stiles extending over one 55
- 20 of said inclined flat bars.
23. In a container of the class described, parallel walls of sheet metal, a structural stiffening member of inverted U-shape extending along the opposite vertical edges 60
- 25 and connecting the tops of two of said parallel walls, and doors hinged to the upright portions of said member and forming substantially an entire container side.
24. In a container of the class described, 65
- 20 a sloping roof, a section of running-board extending along the higher edge of said roof, and a section of running-board extending along a sloping edge of said roof at right angles to said first-mentioned section.
- 30 25. The combination of a carrier and a container, a keeper on one of said parts, fastening means on the other of said parts, and means whereby when said keeper and 70
- 35 fastening means are in engagement, movement of the keeper relative to the fastening means will cause the parts to more tightly engage each other.
26. The combination of a carrier and a container having a substantial base area resting upon said carrier, keeper members located centrally only on the base of said container, and fastening means on said carrier for engaging said keeper members to prevent movement in any direction of said container relatively to said carrier. 75
27. A carrier having oppositely movable fastening members whose paths of movement lie in parallel planes and both cross a line perpendicular to said planes. 80
28. A carrier having pivotally mounted articulated fastening members adapted to swing about disaligned axes cooperatively engaging keeper members and whose arcs of movement overlap in a line parallel with their axes. 85
29. The combination of a carrier, a container, fastening means, means for simultaneously operating and holding certain of said fastening means projected and others retracted. 90
30. The combination of a carrier, container fastening means thereon, means for independently operating said fastening means for different containers, and means for collectively operating and holding said fastening means in their operative or inoperative position. 95

In testimony whereof I hereunto affix my signature this 23rd day of July, 1921.

HENRY W. KIRCHNER.
